“Time Capsule” Modern Casket Rethinks the Burial Container from Manufacturing to Function, posted Nov. 28, 2018 [online], retrieved Apr. 10, 2019, retrieved from internet, <<https://connectingdirectors.com/53077-modern-casket>>.*

Primary Examiner — Barbara Fox
Assistant Examiner — Messina L Smith

(57) **CLAIM**

The ornamental design for a burial capsule, as shown and described.

DESCRIPTION

FIG. 1 is a front-top-left perspective view of a burial capsule showing my new design;
FIG. 2 is a rear-bottom-right perspective view thereof;
FIG. 3 is a top plan view thereof;
FIG. 4 is a bottom plan view thereof;
FIG. 5 is a right elevation view thereof;
FIG. 6 is a left elevation view thereof;
FIG. 7 is a rear elevation view thereof;
FIG. 8 is a front elevation view thereof;
FIG. 9 is a transversal cross-sectional view in the direction of line 9-9 in FIG. 5;
FIG. 10 is a longitudinal cross-sectional view in the direction of line 10-10 in FIG. 3;
FIG. 11 is an exploded front-top-left perspective view thereof;
FIG. 12 is an exploded rear-top-right perspective view thereof;
FIG. 13 is a detail view of the track engagement in FIG. 9; and,
FIG. 14 is a detail view of the track engagement in FIG. 10. The broken lines showing the handles and keyhole depict portions of the burial capsule that form no part of the claimed design.
